UNITED STATES PATENT OFFICE.

HENRY J. SCHMEISER, OF BURLINGTON, IOWA.

TONGUELESS CULTIVATOR.

SPECIFICATION forming part of Letters Patent No. 357,235, dated February 8, 1887.

Application filed October 30, 1885. Serial No. 181,353. (No model.)

To all whom it may concern:

Be it known that I, HENRY J. SCHMEISER, a citizen of the United States, residing at Burlington, Des Moines county, Iowa, have invented a new and useful Improvement in Tongueless Cultivators, of which the following is a specification.

My invention relates to improvements in tongueless cultivators in which a slotted double skein operates in conjunction with an arched axle and a wheel; and the object of my invention is to give a free vibrating lateral motion to the wheel on the axle. I accomplish this by the mechanism illustrated in the accompanying drawings, in which—

Figure 1 represents a full view of my invention from one side, one wheel being removed. Fig. 2 represents a lateral cross-section of the skein, wheel, and coupling. Fig. 3 represents a perspective view of one plow-beam and its connections, looking from the inside. Figs. 4, 5, 6, and 7 are detail views of the skein and standard.

Similar letters refer to similar parts throughout the several views.

In the drawings, A represents the arched axle of a cultivator.

a and a' are the two parts of a double skein, having shoulders a'' and rims r r. These two skeins are bolted together by screw-bolts, as shown in Fig. 6 of the drawings. The double skein a and a' has passing through itself a four-cornered perforation, a³, corresponding to the size of the axle A, which perforation is widened at each end of the double skein horizontally, (see b and b' in Fig. 4 of the drawings,) so as to admit of a lateral movement to and fro of the wheel on the axle A when the same passes through the perforation, as illustrated by the dotted representation of the wheel in Fig. 4 of the drawings. The four-cornered perforation in the double skein a and a' is in the middle of the skein of the exact size of the axle A, as shown in Fig. 4 of the drawings.

c represents the hub of the wheel B, which hub turns upon the double skein a and a', and is put in place by unfastening the bolts herefore mentioned, which pass through the double skein a and a', and hold them firmly together. The axle A is recessed at its end, so as to pass between shoulders a'', and in this recess there is a perforation in the axle for pin

b'' to pass through, by which pin it is held in place. To skein a and a' is bolted the draw-iron C, of the shape as illustrated in the drawings. Inside of wheel B, and upon the axle A, there is fastened by means of a set-screw, x, the coupling D, which is in the shape of a universal joint, as illustrated in Fig. 3 of the drawings.

Gimbal F of the universal joint is adjustably fastened by a bolt, K, through slot h to clamp e, which clamp passes over the plow-beam E, as illustrated in Fig. 3 of the drawings. The gimbal F is provided with cogs, as shown in Fig. 3. To the cross o of the universal joint D are loosely jointed, by bolt or otherwise, the supports g g', which supports are provided with lugs with cogs n, as shown in Fig. 6. These cogs mesh with m. Loosely jointed to plow-beam E is the pronged standard S, of the shape as illustrated in the drawings by Fig. 5.

The operation of my invention is as follows: By means of the widened perforation in skein a a', wheel B is enabled by lateral motion to change the angle with its axle A from a right angle to an oblique angle, and the object of having the double skein is to enable the hub c to be placed on said skein. The object of having the coupling D fastened to axle A by set-screw x is to make the coupling adjustable. When the plow-beam E is lifted up, as shown by the dotted lines in Fig. 1, the supports g g', by means of the meshing of the cogs at m and n, will be pressed to the ground, and will thus support the cultivator in its upright position. The prongs of the standard S will engage with the supports g g', and will thus give support to the plow-beam E. The small lugs p on support g' prevent standard S from slipping down.

The object of having the draw-iron C in the shape as illustrated and fastened to both sides of the skein is to bring the draft on a line with the center of the wheel.

What I claim as my invention, and desire to secure by Letters Patent, is—

1. The skeins a a', having the four-cornered perforations a³ passing through them, and widened at b', in combination with the axle A, corresponding in size with such perforations, as set forth.
2. The skeins a a', having the four-cornered

perforations a^2 passing through them, and widened at b' , and the axle A, corresponding in size with such perforations, in combination with the draw-iron C, bolted to skeins a a' , as set forth.

3. The combination of axle A and the universal joint attached thereto, the latter having the gimbal F, provided with the cogs m , and the support g , having the cogs n , as set forth.

4. The plow-beam E, having the standards S S, in combination with the supports g , the hinged ends of the beams and supports being connected together by intermeshing, whereby

when the beam is raised the supports fall, as set forth.

5. The beam E, having the forked standards S S, and secured to the coupling O, the gimbal F, having the cogs m , and the supports g g' , having the cogs n and lugs p p , all combined and arranged as and for the purpose set forth.

HENRY J. SCHMEISER.
